CIGARETTE REST AND EXTINGUISHER

Wendell W. Jennings, San Francisco, Calif., assignor, by mesne assignments, to Morris Kenes, Stratford, Conn.

Application July 25, 1949, Serial No. 106,624

4 Claims. (Cl. 131—235)

1

This invention relates to cigarette holders or rests and extinguishers, and it has reference more particularly to a combination of an ash tray that is equipped with an extinguishing socket and a cigarette rest that is designed to automatically dump a burning cigarette therefrom into the tray socket to extinguish the cigarette after it has burned down to a certain length.

It is the principal object of this invention to provide a combination of the above character wherein the cigarette rest is mounted for movement between holding and dumping positions and is normally held in position for supporting a burning cigarette thereon by a thermostatic latch element; the said element being so disposed relative to the position of the burning cigarette that when the cigarette burns down to a certain point, the element under effect of the heat will be caused to release the rest and allow it to move by gravity to dump the burning cigarette into the tray with its lighted end projected into the extinguishing socket.

It is also an object of this invention to provide a cigarette rest of an improved form of construction, designed for the support of a burning cigarette over an ash tray, and wherein the cigarette rest is pivoted and supported by a latch that is associated with and released by the action of a thermostatic strip.

Still further objects of the invention reside in the details of construction of the parts of the present device, in their combination and mode of use as will hereinafter be fully described.

In accomplishing the above mentioned and other objects of the invention, I have provided the improved details of construction, the preferred forms of which are illustrated in the accompanying drawings, wherein:

Fig. 1 is a perspective view of a cigarette rest and ash tray combination embodied by the present invention; a part of the tray being broken away for purpose of better illustration.

Fig. 2 is a vertical sectional view of a part of the ash tray, showing the extinguishing socket, and showing the cigarette rest in position for supporting a burning cigarette thereon.

Fig. 3 is a view similar to that of Fig. 2, but showing the cigarette rest after it has been tripped and the cigarette dumped into the tray and extinguishing socket.

Fig. 4 is an outer end elevation of the cigarette rest and its supporting standard.

Fig. 5 is a top view of the cigarette rest or holder.

Fig. 6 is a perspective view of the standard

2

used for the pivotal mounting of the cigarette rest or holder.

Fig. 7 is an enlarged, plan view of the bi-metal thermostatic element employed in the holder.

Referring more in detail to the drawings:

1 designates an ash tray having a bottom 2 and side walls 3. Associated with the tray and resting on the bottom, is a cross member 4 with a downwardly tapered, conical socket 5 of such size that the end of a cigarette may be received therein for extinguishing the burning portion, as shown in Fig. 3.

Supported at one side of the tray is a cigarette rest embodying therein certain improvements of the present invention; this rest being designed for the support of a burning cigarette therein as has been illustrated best in Fig. 2. The rest comprises a mounting standard 10, best shown in Fig. 6 as comprising a flat, vertical plate 10a of metal or other suitable material. This standard is adapted to be fitted at its lower end in a vertical slot or socket 11 that is formed in the cross piece 4, adjacent a side wall of the tray, thus to hold it rigidly in upright position. The upper end portion of the standard extends above the edge of the side wall of the tray and there supports a trough-like member 12 in which a burning cigarette may be rested as shown in Fig. 2. The member 12 is of sufficient width and length to permit a cigarette to be easily laid therein and easily picked up. It is formed along its opposite side edges with depending flanges 13 between which the upper end portion of the standard 10 is received, as noted in Fig. 4.

The standard is formed at its upper end and at opposite edges with outwardly extending trunnions 15, as best noted in Figs. 4 and 6, which are contained in holes 16 that are formed in the flanges 13 of the trough-like member, thus to pivotally attach the rest 12 to the standard for its movement between the supporting and dumping positions in which it is shown in Figs. 2 and 3, respectively.

When the rest 12 is in the horizontal position as shown in Fig. 2, it is held against outward tilting about its supporting trunnions by reason of the bottom thereof resting against a laterally turned flange 17 formed at the upper end of the standard. It is releasably held in this cigarette supporting position by means of a latch element that is associated with a thermostatic element 20 carried by the rest as well as shown in Fig. 1.

The element 20 comprises a single, elongated bi-metal strip that, at one end, is rigidly attached 55 as seen in Fig. 7 to one of the depending side

flanges 13 of the trough-like member 12 designated as the rest. The strip 20 is bent back and forth in a succession of loops to extend in a transverse direction across the inner end of the rest as noted in Fig. 1. The free end of this strip is turned directly outward as a latch element 22, and it is extended through a longitudinal slot 23 in the other side flange 13 of the rest and then projects into an arcuate slot 24 formed in a flange 25 that extends inwardly from the upper end portion of the standard 10. The arcuate slot 24 is formed in the flange 25 about the axial line of the trunnions 15 as a center. At its upper end the outside edge of the arcuate slot is formed with an inwardly and horizontally extending enlargement having an upwardly facing shoulder 30 upon which the out-turned portion 22 of the thermostatic element normally seats, as seen in Fig. 2, thus to hold the rest 12 in the horizontal position in which it is shown in Fig. 2.

The thermostatic strip is exposed adjacent to the inner end edge of the rest 12. Therefore, if a cigarette as placed on the rest 12 burns down to a point adjacent this strip, the heat of the burning portion acts on the strip 20 to cause it to be warped and its free end moved off the supporting shoulder 30.

It is to be explained further that that portion of the holder or rest 12 that overhangs the ash tray is sufficiently heavier than the outer end portion so that when the latch is released from supporting contact with the shoulder, the rest swings to the position of Fig. 3 and the supported cigarette will be dumped into the socket as shown.

Assuming the parts to be so constructed and assembled as described, the use and operation of the combined holder and tray would be as follows: The lighted cigarette 50 is placed in the support or rest 12 as shown in Fig. 2, with its lighted end overhanging the ash tray. When the cigarette burns to such an extent that the heat from the burning portion comes into contact with the thermostatic element, the heat therefrom so affects the element that it moves from the full line position of Fig. 7 to the dotted line position. By this movement, the out-turned end portion 22 of the element is shifted from the supporting shoulder 30 at the upper end of the arcuate slot 24 and the pivoted rest 12 is permitted to swing to the position of Fig. 3. When the rest so swings, the cigarette will be dumped into the tray and its lighted end will be projected into the extinguishing socket, thus extinguishing the cigarette, the socket being so located as to receive the cigarette.

One advantage of this device resides in the fact that the dumped cigarette will be extinguished and not become a fire hazard or obnoxious by reason of smoke and odor.

Another advantage found in the present device resides in the freedom of action of the thermostatic element. The shape of the bi-metal thermostatic element permits free air passage for complete combustion of a cigarette plus rapid action of the fully exposed element both in heating and cooling. This factor assures the desired dumping of the cigarette and also permits substantially immediate resetting of the rest.

To reset the device from the position of Fig. 3 to that of Fig. 2, it is only necessary to press down on the outer end of the rest and swing

it to horizontal position, at which the latch element adjoining engages upon the shoulder 30.

This device may be applied in various ways to trays of different kind and it not to be restricted as to size or to the type or design of ash tray. It is adaptable for use with cigars as well as with cigarettes.

Having thus described my invention, what I claim as new therein and desire to secure by Letters Patent is:

1. In combination, a receptacle equipped with a cigarette extinguishing socket, a standard, a rest plate pivotable on said standard and on which a burning cigarette may be rested in a definite position relative to the receptacle socket, and a thermostatic element associated with said standard and plate and normally supporting the plate in position for retaining the cigarette thereon, and movable under the influence of heat from the burning cigarette to release the said plate for the dumping of the cigarette therefrom and projecting its burning end into the said extinguishing socket.

2. In combination, an ash tray equipped with a cigarette extinguishing socket, and a cigarette holder comprising a standard, a cigarette rest plate pivotable on said standard for resting a burning cigarette in a definite position relative to the socket, and a thermostatic element fixed to the rest plate in position for holding the rest plate in position to support a burning cigarette thereon and adapted to be moved by heat from the burning cigarette to effect release of the pivoted rest for gravity movement whereby the cigarette will be dumped and deposited with its lighted end projected into said extinguishing socket.

3. A holder for burning cigarettes comprising a supporting standard, a trough-like cigarette rest plate pivoted near its outer end on said standard to swing from a horizontal cigarette-supporting position to a downwardly inclined cigarette-dumping position, a laterally turned flange on said standard formed with an arcuate slot centered about said pivot axis of the plate, and having an upwardly facing shoulder formed in an enlargement thereof near its upper end, and a thermostatic bi-metal strip attached at one end to the rest plate and extended across the inner end thereof and having a free end portion normally engaged with said shoulder for the support of the rest plate in said horizontal position, and adapted to be affected by heat of a burning cigarette placed on the rest plate, to cause the strip to be disengaged from the shoulder thus to permit the rest plate to swing to dumping position for endwise discharge of the cigarette therefrom.

4. A device as recited in claim 3 wherein the standard has means thereon for engagement by the rest plate to limit the outward tilting thereof.

WENDELL W. JENNINGS.
